E. W. BARRETT

SUPPORTING MEANS FOR LOOM PICKER SPINDLES

Filed Aug. 11, 1925

UNITED STATES PATENT OFFICE.

EDWIN W. BARRETT, OF BOSTON, MASSACHUSETTS, ASSIGNOR TO THE STAFFORD COMPANY, OF BOSTON, MASSACHUSETTS, A CORPORATION OF MASSACHUSETTS.

SUPPORTING MEANS FOR LOOM PICKER SPINDLES.

Application filed August 11, 1925. Serial No. 49,562.

The invention has relation to means for supporting upon the lays of looms the spindles or rods upon which, in the case of some looms, the pickers are mounted, and along which the pickers slide in throwing the shuttle. In practice, a spindle or rod of such class is mounted fixedly upon a loom lay at either end of the lay-beam, adjacent the correspondingly located shuttle-box or shuttle-boxes. On account of the effect of the picker movements along a picker-spindle or rod, and on account of the jarring and vibration due to lay movements, and the resulting tendencies to movements and to vibration of the picker-spindle or rod, and consequent wear of the spindle or rod and the mountings or supports, difficulty has been experienced in the past in supporting and holding a picker-spindle or rod so that it will be kept securely in position upon a loom lay, and in preventing looseness and excessive vibration thereof.

The objects of the present invention are to provide novel and improved means of securing a picker-spindle or rod in the supports or mountings therefor; to provide improved means for compensating for wear; and to provide for the replacement of a worn spindle seat.

Illustrative embodiments of the invention are shown in the accompanying drawings, in which,—

Fig. 1 is an elevation of parts at one end of the lay of a loom, showing shifting shuttle-boxes, and also indicating the application of one embodiment of the features of the invention.

Fig. 2 is a plan view of the parts which are shown in Fig. 1.

Fig. 3 is a plan view of the picker-spindle or rod of Figs. 1 and 2 and its more immediate mountings or supports.

Fig. 4 is a horizontal section on a larger scale, of the spindle-retaining means which is indicated in Figs. 1, 2 and 3 in connection with the outer end of the picker-spindle or rod.

Figs. 5 and 6 are views similar to Fig. 4, showing modifications of the retaining means.

Fig. 7 is a view in horizontal section of the mounting or support at the inner end of the picker-spindle or rod, and the renewable

wear-receiving member or bushing that is combined therewith.

Having reference to the drawings,—

Only so much of the lay-beam of a change-box or shifting shuttle-box loom, and the parts that are combined therewith, as is necessary for a clear understanding of the invention, is shown in the accompanying drawings. The lay-beam is indicated at 1, and at 2 are shown the shuttle-boxes, which in this instance are shifted vertically to bring any desired one of the various shuttles carried therein into working relation with respect to the shuttle-race of the lay, and to a picker 3 which propels the shuttle across the loom. At 4 is shown a fixed picker-spindle or rod upon which the said picker is mounted for movement lengthwise of the lay under the actuation of a picker-stick 5, (only a portion of which is shown,) which last in practice is actuated in familiar manner. At 6, 7, are mountings or supports for the picker-spindle or rod, projecting rearwardly from the lay, and by means of which the said spindle or rod is supported upon the lay in proper relations with the shuttle-race and shuttle-boxes. The opposite end-portions of the picker-spindle or rod occupy 80 sockets or seats in connection with these mountings or supports.

Referring now to the features which are more particularly material to the invention:—

The mounting or support at one end of the picker-spindle or rod, for example the mounting or support 6 at the inward end thereof, as in the drawings, is constructed or provided with an end-stop for the said spindle or rod. The mounting or support at the other end thereof, in this case the mounting or support 7, has associated therewith adjustable means acting against the latter end, axially of the latter, to hold the spindle or rod endwise, with the first-mentioned end thereof within the socket or seat of the corresponding mounting or support, and in engagement with the said end-stop. Preferably, as in the drawings, the said mounting or support 6 at the inward end of the spindle or rod is formed with an elongated tapered socket which receives the corresponding end-portion of the spindle or rod, and such end-portion

tion of the spindle or rod is formed correspondingly so as to terminate in an elongated taper fitting the socket, as illustrated best in Fig. 7, in order that the said end-portion may fit properly within the said tapered socket and have elongated bearing contact with the wall thereof. The converging portions of the wall of the tapered socket serve to limit the extent to which the tapered spindle end can enter into the socket, and consequently the tapered socket constitutes an end-stop for the spindle or rod. In the drawings, the mounting or support 7 at the outward end of the spindle or rod is formed with a hole therethrough of a diameter corresponding closely with that of the spindle or rod, so that the end-portion of the spindle or rod fits snugly within the said hole. In the drawings, also, the said mounting or support 7 is provided with adjustable means such as aforesaid arranged, etc., to act against the outward end of the spindle or rod, axially of the latter. Several forms of such adjustable means are shown in the drawings, all being on the order of screw devices; still other forms may be employed, including devices of other types as well. In the case of the illustrated embodiments of the invention, the adjustable means is in screw-threaded engagement with the mounting or support 7, and is essentially what may be termed a screw adjustment device. In these particular instances the wall of the hole in mounting or support 7 is screw-threaded, and the adjustment device, or at least its acting portion, is a screw and is entered and screwed into the said hole. Usually, the inner end of the said screw engages directly with the end of the spindle or rod, as shown, although this direct engagement is not material. The screw may be screwed inward, as may be required, in making adjustments to cause the inward end of the spindle or rod to engage with the end-stop, and hold such end in contact therewith, and may be screwed outward, (and completely removed when necessary,) in order to loosen the spindle or rod and to permit its removal when desired.

In Figs. 1, 2, 4, and 5, the adjustment device is a headless screw 11, which is screwed completely into the hole or passage of the mounting or support 7. I find it advisable to employ locking means in connection with the adjusting screw 11, for the purpose of preventing accidental unscrewing of the latter as a result of the jarring and vibration in the case of the lay and the parts carried thereby, while the loom is in operation. The locking means in Figs. 1, 2, and 4, is a headless screw 12 which is screwed into the passage or socket 10 in the mounting or support 7, until the inner end of such screw 12 makes contact with the outer end of the adjusting screw 11. The screws 11 and 12 are formed with non-cir-

cular recesses for the reception of a convenient tool or key used for turning the same. In the case of the construction shown in Fig. 5, the locking means is a machine-screw 17 having a polygonal head adapted to have applied thereto a suitable wrench. In the case of the construction shown in Fig. 6, the adjustment screw is a long headed machine screw, and the locking means is a locknut 14 mounted upon the portion of the screw-threaded stem of the said screw which is outside the hole 10 in the mounting or support 7, the said locknut making contact with the adjacent side of the said mounting or support. The rapid movements of the lay of a loom forward and backward during operation have a tendency to cause transverse vibrations of the picker-spindle or rod in forward and rearward directions. These vibrations tend to cause wear of the sockets or holes that are occupied by the end-portions of the said spindle or rod. As wear progresses, it permits forward and rearward play of the picker-spindle end-portions, such play increasing in extent as the wear of the walls of the sockets or holes progresses. One feature of my invention consists in a socket-piece which is detachably applied to a loom-lay, and which may be removed when wear has occurred, and replaced by a fresh one. The drawings illustrate this feature of the invention as employed in connection with the mounting or support 6. Thus, in Figs. 2, 3, and 7, a bushing 8 is shown applied to the mounting or support 6 in a manner providing for ready and convenient application and fastening, or unfastening and removal. The mounting or support 6 is formed with a hole into which the body of the bushing 8 fits, the bushing having a flange 9 which makes contact with one side of the said mounting or support, and the bushing body being screw-threaded and having applied thereto a nut 81 which is turned up against the opposite side of the mounting or support 6, in order to fasten the bushing in place. The nut 81 may be unscrewed from the bushing when it is desired to remove the latter. The socket or seat for the corresponding end-portion of the picker-spindle or rod 4 is formed in the bushing 8. In Fig. 7 the said socket or seat is shown as tapered, as described hereinbefore. As will be apparent, a similar renewable bushing may be combined with the mounting or support 7.

What is claimed as the invention is:—

1. The combination with a picker-spindle or rod having one end thereof terminating in an elongated taper, and supports at the opposite ends of said spindle or rod by which the latter is mounted upon the lay of a loom, of a member removably combined with one of said supports, having a seat corre-

spondingly tapered and fitting the said tapered end, and an adjustment screw in connection with the other support abutting by its inner end against the proximate end of the spindle or rod and by which the latter may be controlled endwise to keep the tapered end properly engaged with the tapered seat.

2. The combination with a picker-spindle or rod, and supports at the opposite ends thereof by which the spindle or rod is mounted upon the lay of a loom, one of said supports having a hole therethrough, of an externally screw-threaded bushing occupying such hole, fitting the corresponding end-portion of the spindle or rod and providing an end-stop therefor, and also having an external shoulder in engagement with one side of such support, a nut upon said bushing engaging the other side of said support, and adjustment means in connec-

tion with the other support by which the spindle or rod is adjusted endwise into engagement with said end-stop.

3. The combination with a picker-spindle or rod having one end thereof tapered, and supports at the opposite ends thereof by which the spindle or rod is mounted upon the lay of a loom, one of said supports having a hole therethrough, of an externally screw-threaded bushing occupying such hole, having a tapered seat for the tapered end of the spindle or rod, said bushing having an external shoulder in engagement with one side of such support, a nut upon said bushing engaging the other side of said support, and adjustment means in connection with the other support by which the spindle or rod is adjusted endwise into said tapered seat.

EDWIN W. BARRETT.
